Specification for Design.

Patented June 8, 1915.

Application filed December 4, 1914. Serial No. 875,541. Term of patent 7 years.

To all whom it may concern:

Be it known that I, LUTHER D. SMITH, a citizen of the United States, residing at Toledo, in the county of Lucas and State of Ohio, have invented a new, original, and ornamental Design for a Stove, of which the following is a specification, reference being had to the accompanying drawing, forming a part thereof.

In the drawing, Figure 1 is a front ele-

vation, and Fig. 2 is an end elevation of a stove showing my new design.

I claim:

The ornamental design for a stove, substantially as shown.

LUTHER D. SMITH.
